(57) **CLAIM**

The ornamental design for a projector equipment attached to vehicle, as shown and described.

DESCRIPTION

FIG. 1 is a front perspective view of the front, left, and top sides of a projector equipment attached to vehicle showing our new design;

FIG. 2 is a front view thereof;

FIG. 3 is a rear view thereof;

FIG. 4 is a right side view thereof, the left side view being a mirror image thereof;

FIG. 5 is a top plan view thereof, the bottom view being a mirror image thereof;

FIG. 6 is a cross-sectional view taken along line 6-6 in FIG. 2;

FIG. 7 is a front perspective view, shown within a first environment of use; and,

FIG. 8 is a top plan view, shown within a second environment of use.

The broken lines shown in FIGS. 1-7 depict portions of the article that form no part of the claimed design. Additional broken lines in FIG. 7 and the broken lines in FIG. 8 depict environmental subject matter that forms no part of the claimed design.

1 Claim, 8 Drawing Sheets
